(57) **CLAIM**

The ornamental design for an electric shaver handle, as shown and described.

DESCRIPTION

FIG. 1 is a front, right and top perspective view of an electric shaver handle, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a front, right and top perspective view thereof shown in a first environment of use;

FIG. 10 is a front, right and top perspective view thereof shown in a second environment of use;

FIG. 11 is a front, right and top perspective view thereof shown in a third environment of use;

FIG. 12 is a front, right and top perspective view thereof shown in a fourth environment of use;

FIG. 13 is a front, right and top perspective view thereof shown in a fifth environment of use;

FIG. 14 is a front, right and top perspective view thereof shown in a sixth environment of use; and,

FIG. 15 is a front, right and top perspective view thereof shown in a seventh environment of use.

The broken lines illustrate portions of the electric shaver Handle and form no part of the claimed design. Additional broken lines shown in FIGS. 9-15 showing attachments illustrate environmental subject matter and form no part of the claimed design.

1 Claim, 15 Drawing Sheets
